UNITED STATES PATENT OFFICE.

CHARLES M. CRANE, OF CANTON, OHIO, ASSIGNOR TO THE GILLIAM MANUFACTURING COMPANY, OF SAME PLACE.

DESIGN FOR A HARNESS-SADDLE.

SPECIFICATION forming part of Design No. 33,253, dated September 25, 1900.

Application filed August 25, 1900. Serial No. 28,078. Term of patent 7 years.

To all whom it may concern:

Be it known that I, CHARLES M. CRANE, a citizen of the United States, residing at Canton, in the county of Stark and State of Ohio, have invented and produced a new and original Design for Harness-Saddles, of which the following is a specification, reference being had to the accompanying drawings, forming part thereof.

Figure 1 is a front elevation of a harness-saddle, showing my design. Fig. 2 is a plan thereof, and Fig. 3 is a vertical section on the line 3 3 of Fig. 1.

As shown in the drawings, the leading or material features of my design consist in a pad of V shape, shown curved on its under side and designed to fit the horse's back, and on the upper side of this a housing extending down on each side considerably beyond the end of the pad, and on the upper side of the housing a skirt extending down still farther, and on the upper side of the skirt a jockey, the point of the housing coming about midway between the point of the jockey and the point of the skirt. Secured to the lower end of the skirt is a billet, and on the upper side of the

skirt extending from beneath the jockey is the bearing.

Referring to the parts by letters, A represents the pad, and B the housing, which, as shown, has its edge wavy and is beaded and stitched near the edge.

C represents the skirt; D, the billet secured thereto; F, the jockey, and G the bearing.

By having the housing extend down substantially midway between the jockey and the point of the skirt a very neat and graceful appearance is obtained, and, as stated, this extension of the housing is one of the essential features of my design.

Having described my invention, what I claim as new, and desire to secure by Letters Patent, is—

The design for a harness-saddle, substantially as herein shown and described.

In testimony whereof I hereunto affix my signature in the presence of two witnesses.

CHARLES M. CRANE.
